(57) **CLAIM**

The ornamental design for a toilet roll dispenser as shown and described.

DESCRIPTION

FIG. 1 is a perspective view of a toilet roll dispenser, showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a cross-sectional view thereof taken along lines 8-8 in FIG. 6.

The broken lines in the drawings illustrate portions of the toilet roll dispenser that form no part of the claimed design.
